UNITED STATES PATENT OFFICE.

HENRY E. HOLBROOK, OF BOSTON, MASSACHUSETTS.

FUEL-CONTROLLING MEANS.

Application filed August 19, 1918. Serial No. 250,599.

To all whom it may concern:

Be it known that I, HENRY E. HOLBROOK, a citizen of the United States, residing at 67 Robin Street, West Roxbury, Boston, in the county of Suffolk, and Commonwealth of Massachusetts, have invented an Improvement in Fuel-Controlling Means, of which the following description, in connection with the accompanying drawings, is a specification, like characters on the drawings representing like parts.

This invention relates to fuel controlling means, for internal combustion engines, and its object is to provide an improved construction for this purpose.

In the drawings of the embodiment of my invention illustrated and described herein,

Fig. 1 is a side elevation of my invention as installed on an internal combustion engine of conventional construction;

Fig. 2, a plan of the valve, showing in dotted lines the spindle in closed position;

Fig. 3, a vertical longitudinal section of the valve on the line 3—3, Fig. 2;

Fig. 4, a view similar to Fig. 2, showing the spindle in section on the line 4—4, Fig. 3, and as open in relation to the vapor intake pipe;

Fig. 5, a similar view, showing the spindle open to both the vapor intake and priming passages;

Fig. 6, a similar view showing the spindle open only to the priming passage.

It is commonly recognized that a small amount of moisture contained in the mixture of air and gas ordinarily supplied to an internal combustion gasoline engine will not only cause the engine to run more quietly, but it will also act to prevent the formation of carbon on the cylinder walls and the pistons. The moisture also improves the explosive quality of the mixture, giving greater power.

Referring first to Figs. 1 to 6 inclusive, my novel invention comprises a vapor intake pipe 1, preferably connected to the overflow pipe 2, of the radiator 3, intermediate its ends, and running to a valve 4, which may be positioned at any convenient point on the dash 5.

A second vapor outlet pipe 6, connects the valve 4 with the manifold 7 of the engine 8. Obviously these pipes may be carried to any part of the dash and on either side of the

engine that may be most convenient according to the particular construction in use. The pipe 1, for engines of small size, is preferably 1 inch diameter, while the pipe 6, for reasons which will appear presently, is preferably somewhat larger as for instance 1 1/2 inches. These pipes may be conveniently connected to both the radiator overflow pipe and the valve 4, by the usual solderless connections.

My invention comprises also a novel form of valve for controlling the supply of vapor which, as shown herein, Figs. 2, 3, comprises a body 4, of any preferred form, herein substantially rectangular or block like and of convenient size. The body 4 has a lateral vapor inlet passage 9, into the outer end of which is threaded the connection 10 upon the end of the vapor inlet pipe 1. The body is also provided with a similar vapor outlet passage 11 which may be connected to the outlet pipe 6 in the same manner by a connection 12.

The passages 9, 11, Figs. 2, 3, both enter a main longitudinal connecting passage 13, which passage takes an upward turn at one end, and opens to the atmosphere providing a priming opening 14.

For establishing communication between these several passages 9, 11, 13, at will, Figs. 2, 3, and in any desired combination, I provide a novel universal valve spindle 15. This spindle is, herein, hollow, seated in a suitably shaped opening in the body 4, at the junction of the passages 9, 13, forming a mixing chamber 15^a, wherein the vapor admitted through port 9 and the priming charge and air, or either of them, admitted through the port 14 may be mixed before it is discharged through port 11 of the manifold and is provided with a knurled edge 16 at its upper end for convenient manipulation. The valve may be retained on its seat in the body 4 by any convenient means as for instance a narrow annular slot 17, to which is positioned a finger 18, formed, as 100 of metal, which may be secured by a screw 19, to the body 4.

This spindle 15, Fig. 2, is provided with ports 20, 21, 22. Normally, the ports will occupy the positions shown in dotted lines, Fig. 2, connection between the passages 9 and 11 being interrupted. In this position, the valve permits neither the introduction

of vapor into the manifold 7, nor the use of the priming opening 14 which will be referred to presently.

When it is desired to introduce vapor into the manifold, the valve is turned to position shown in Fig. 4, where it will be seen the port 21 registers with the passage 9, leading to the vapor inlet pipe 1 and the port 20 registers with the vapor outlet passage 13.

10 When in this position obviously vapor will be drawn from the radiator by the suction of the pistons and fed into the manifold 7 and there mixed with the usual charge of gas and air. The valve may, of course, be 15 opened part way or to its full extent as may be desired.

When it is desired to not only draw vapor from the radiator, but, for any reason, as for instance when running on level ground 20 or on a long down grade, it is also desirable to draw more vapor from the atmosphere and lean the mixture, then the spindle will be positioned as shown in Fig. 5, where the port 20 of the spindle registers with the passage 9 and the port 21 registers with the passage 13, and establishes communication between the priming opening 14, while the passage 22 registers with the passage 13 to the vapor outlet pipe thus providing both 25 vapor and air in any desired quantity.

When, again, it is desired simply to use the priming opening 14 for the introduction of a charge of priming liquid to start the engine, such as gasoline or ether, then the 35 spindle will be positioned as shown in Fig. 6, so that while the ports 21, 22, will establish communication between the priming opening 14 and the vapor outlet passage 13, the vapor inlet passage 9 will be closed.

40 When in this position the priming liquid will be drawn through the valve into the manifold by the pistons in the usual manner.

In some cases the moisture has been supplied by drawing air through a body of water thus saturating it with moisture and then feeding it into the manifold or intake pipe of the engine, while in other cases the vapor has been obtained from the radiator which is usually warm after the car has 50 been driven a few miles, and soon thereafter becomes so hot as to supply a vapor continuously. Sometimes also an auxiliary steam forming device is used.

When taking the vapor from the radiator 55 direct, one meets the objection that if the radiator is full there is danger that water instead of vapor will be drawn from the vapor intake pipe and supplied to the combustible charge. On the other hand if the 60 vapor inlet pipe is connected to the outer end of the overflow pipe from the radiator I have discovered that more air is drawn

from the atmosphere than vapor from the radiator, so that the desired amount of moisture is not always obtained.

I have discovered that there are advantages over either of the above noted methods of obtaining moisture which may be availed by taking the vapor from the overflow radiator pipe intermediate its ends. 70 By so doing, the vapor which seeks to escape from the radiator through the overflow pipe is intercepted before it reaches the outlet and becomes more or less mixed with the outside air.

If the vapor is not formed, owing to the fact that the radiator has not become warm, or owing to the fact that the cold weather may possibly prevent the formation of vapor, pure air can be obtained if desired 80 through the overflow pipe.

While I have disclosed herein one embodiment of my invention, it will be obvious that many changes in detail may be made therein without departing from the spirit of my invention and all within the scope of the appended claims.

Claims:

1. A valve having a body, a fuel and air inlet priming port in the upper face thereof, vapor inlet and outlet ports on one side thereof, a hollow valve spindle seated in said body and through the top thereof, a mixing chamber in said valve spindle, ports in said valve spindle registering with the fuel inlet and vapor inlet and vapor outlet ports, for effecting selective connections between the fuel and air inlet and vapor inlet ports, or either of them, on the one hand, and the vapor outlet port on the other hand, 90 a locking groove on the outer wall of said valve spindle and a locking finger on the body and seated in said groove.

2. A valve comprising the body 4, having the fuel and air inlet port 14 on its upper 105 face, vapor inlet port 9 and vapor outlet port 11 on one side of the body, a hollow valve spindle 13 in the upper face of the body with a mixing chamber 15^a therein, ports 20, 21 and 22 in the wall of said valve 110 spindle, the chamber 15^a being larger than the cross-sectional area of said ports and always connecting at least two of the ports, said ports also registering with ports 9, 11 and 14 in the valve body to permit selective 115 connections between the ports 14 and 9 or either of them on the one hand, and port 11 on the other hand, a groove 17 in the outer wall of the spindle and a valve spindle locking finger 18 on the upper face of the body 120 and seated in said groove.

In testimony whereof, I have signed my name to this specification.

HENRY E. HOLBROOK.
